HERBERT M. DAWLEY, OF BUFFALO, NEW YORK, ASSIGNOR TO THE PIERCE-ARROW
MOTOR CAR COMPANY, OF BUFFALO, NEW YORK.

DESIGN FOR A VASE.

40,562.

Specification for Design.

Patented Mar. 8, 1910.

Application filed November 17, 1909. Serial No. 528,627. Term of patent 14 years.

To all whom it may concern:

Be it known that I, HERBERT M. DAWLEY, a citizen of the United States, residing at Buffalo, in the county of Erie and State of New York, have invented a new, original, and ornamental Design for Vases, of which the following is a specification.

The accompanying drawing represents a perspective view of a vase embodying my design.

The design comprises as its main feature the downwardly tapering octagonal body having a flaring or trumpet-shaped upper end with an octagonal outer periphery and a circular inwardly converging mouth.

I claim:

The ornamental design for a vase, substantially as shown and described.

HERBERT M. DAWLEY.
